UNITED STATES PATENT OFFICE.

MASCHIL D. CONVERSE, OF NEWARK, NEW JERSEY, ASSIGNOR, BY MESNE ASSIGNMENTS, TO HOWLAND METALLIC CAP COMPANY, OF NEW YORK, N. Y., A CORPORATION OF NEW YORK.

CLOSURE FOR JARS, BOTTLES, AND LIKE RECEPTACLES.

No. 873,989.

Specification of Letters Patent.

Patented Dec. 17, 1907.

Application filed January 14, 1907. Serial No. 352,202.

To all whom it may concern:

Be it known that I, MASCHIL D. CONVERSE, a citizen of the United States, residing at Newark, in the county of Essex and 5 State of New Jersey, have invented certain new and useful Improvements in Closures for Jars, Bottles, and Like Receptacles, of which the following is a specification.

My invention relates to metallic closures 10 for bottles, jars, and other like receptacles, and more definitely to that class of such articles composed of more than one piece of metal, and designed to be applied on the mouth of the receptacle under exterior mechanically applied downward pressure, while 15 a holding member is also by mechanical means and at the same time turned under the shoulder of the neck of the receptacle in sealing.

20 The objects of my invention are to provide an effective, neat appearing and inexpensive closure of this type, that may be mechanically applied expeditiously and with safety and certainty, and that may readily be unsealed without the use of a key or other implement; a further and special object being 25 to provide a closure which may be manually sufficiently well replaced upon the receptacle to serve against spilling of its contents while 30 being intermittently dispensed, by moderately re-sealing the same, or optionally so that a separably fitted outer cup or shell, forming part of my invention, may alone be used as a simple lid or cover for the unsealed 35 receptacle and the inner cap or shell discarded.

My invention in preferred form comprises two cup-shaped parts, one within the other, the inner and deeper one having its depending and, preferably, slightly flaring flange divided vertically in a plurality of places entirely from bottom to top, and made of thin non-resilient, readily bendable metal sufficiently ductile to permit of its lower 45 edge being turned by mechanical appliance under the shoulder of the neck of the receptacle in sealing the same; the outer cup being separably fitted over the inner one and preferably having a non-flaring, straight, or 50 nearly straight, and solid circumferentially continuous, depending flange considerably shorter than the flange of the inner cap, serving, first, to keep the divided sections of the inner cap from disengagement radi-

ally with the shoulder after they have been 55 mechanically applied to the same, and, secondly, serving either to perform a like service, on manual returning of the entire closure to the mouth of the receptacle for temporary closure thereof, or, after discarding 60 the inner cup, to be used alone as a lid or cover only therefor, after first unsealing.

My invention further comprises other advantageous features in structural form, all which are hereinafter fully set forth and 65 definitely claimed.

In the drawings: Figure 1 is a plan or top view of the outer shell or cup. Fig. 2 a cross-sectional elevation of the same. Fig. 3 is a side elevation, partly sectional, of the inner 70 cup or shell, and Fig. 4 an edge view of the disk of cork or other suitable sealing medium. Fig. 5 shows my invention assembled and upon the mouth of a bottle in position for being by mechanical means secured thereto. 75 Fig. 6 is an internal view of the inner shell. Fig. 7, partly sectional, shows my invention complete as it appears after having been mechanically secured on the bottle in sealing the same, and also shows in part the method 80 of manual removal or unsealing. Fig. 8 further shows the method of and action in manually unsealing. Figs. 9 and 10 are respectively a partly sectional elevation and a plan view showing two modifications of 85 form of the outer cup or shell, one thereof for facilitating its removal, and the other to economize material, all which will now be more fully described in detail.

Like letters indicate corresponding parts 90 throughout the several figures.

A is the outer shell, and *a* an external annular bead at the margin on its top, but which may be dispensed with, as its use is chiefly for ornamentation. 95

B, is the inner shell, which is preferably made slightly flaring, and of quite thin and fairly ductile metal, the depending flange being divided or slit vertically the entire depth thereof, at *b b*, in a number of places, more or less, according to the diameter of the cap; those for use on small mouthed receptacles requiring fewer slits than larger ones. C, is a disk of cork or other suitable sealing medium, inclosed in this inner shell (see Figs. 5, 7, 8 105 and 9).

*b*², Figs. 7, 8 and 9, shows the depending flange of the inner shell as it appears when

bent under the shoulder, d^2 of the top, d , of the bottle, D, in sealing of the latter.

a^2 , in Figs. 9 and 10, shows a modified form 5 of the outer shell, A, that may be employed consisting of a row of external, radially projecting semi-spherical beads, preferably at or near the upper margin of the shell, to facilitate removal of this shell, as will hereinafter be shown.

10 Fig. 10 shows also another modification consisting of the cutting out of a disk K from the top of the outer shell, A, making an opening from a^3 to a^3 , as shown, especially practicable in the larger sizes of closures used on 15 wide mouthed receptacles, because from the disk K so cut out shells for smaller closures may be drawn, or stamped. It will be seen that thus opening the top of the outer shell still leaves an inwardly extended flange, 20 shown at a, Fig. 10, for engagement with the peripheral margin of the top of shell B.

It will readily be seen by those skilled in the art that my improved closure can be manufactured economically and with great 25 facility.

The operation of my invention is as follows: As a finished product, made as described, and assembled as shown in Fig. 5, it is, with a disk of sealing medium inclosed, placed upon 30 the top of a receptacle to be sealed, and by well known mechanical devices applied to the exterior surface of the top of the outer cap, pressed down upon the same very firmly to the position shown in this figure; then, 35 while so under pressure, the lower depending edge, b^2 (Fig. 7), of the inner shell only is, also by mechanical means securely bent under the annular shoulder of the receptacle, thus sealing the same, the depending but shorter 40 continuous flange of the outer shell, at its lowest margin, by snugly embracing the sections of the flange of the inner cap at a circumferential line just at or slightly above the bend line of the undeturned part, b^2 , effectually 45 keeps the latter from disengagement with the shoulder d^2 , during and after such mechanical application. To open or unseal a receptacle so sealed, with my improved closure, place the thumb against one side, as 50 in Fig. 7, and press forcibly against the outer shell, which latter, having greater diameter at the top inside than the external diameter of the top of the inner shell, (a feature of my present invention) is in consequence and by 55 this means readily pushed over slightly. It is then pushed in like manner from the opposite side, when it will be found to be loosened and quite easily removable.

If the beaded (a^2 a^2) construction shown in 60 Figs. 9 and 10, or any similar circumferentially extended undulated or roughened exterior is employed, then the shell, A, may be removed by grasping it firmly with the hand,

these beads, or their equivalent, affording a good grip thereon, but the before defined differing diameters of the caps or shells at their tops should be employed. Now, the outer shell having been removed, the sections of the slotted flange of the inner shell may successively be pried out from under the shoulder 65 of the bottle by the thumb or finger nail with ease, safety and facility, as shown in Fig. 8, because, first, the slits, b b, extend entirely to the horizontal plane of the interior surface of the top and, secondly, because the metal 70 being thin and ductile readily bends at the point e across the top of the shell in a straight line from the upper terminals of adjacent slits, so that no implement is required in this 75 unsealing.

If the contents of the receptacle are to be intermittently used, then the closure may be manually replaced entire, and sufficiently well to prevent spilling. If only a lid or cover 80 is desired, then the outer shell only is used, the inner one being discarded, except in case of the modification where the top of this outer shell may be cut out, when it would not so serve.

Having described my invention, what I 90 claim as new, and desire to secure by Letters Patent, is:

1. In a metallic closure of the class described, in combination, an inner cap, adapted to inclose a disk-shaped sealing medium 95 and to be applied to receptacles as set forth, having a non-resilient ductile dependent flange plurally divided its entire depth, and an outer separably fitted removable cap, inclosing the former, of greater interior diameter at its top than the external diameter of 100 the top of the inclosed cap and in circumferential engagement at its lower edge with the flange sections of the latter just above the lower edges thereof. 105

2. In a metallic closure of the class described, in combination, an inner cap, adapted to inclose a disk-shaped sealing medium and to be applied to receptacles as set forth, having a non-resilient ductile dependent flaring flange plurally divided its entire depth and an outer separably fitted removable cap, inclosing the former, of greater interior diameter at its top than the external diameter 110 of the top of the inclosed cap and in circumferential engagement at its lower edge with the flange sections of the latter just above the lower edge thereof. 115

In testimony whereof I have signed my name to this specification in the presence of 120 two subscribing witnesses.

MASCHIL D. CONVERSE.
